CLAIM

The ornamental design for an abrasive sheet, as shown and described.

DESCRIPTION

FIG. 1 is a perspective view of an abrasive sheet in accordance with the invention disclosed and claimed herein; FIG. 2 is a top plan view of the abrasive sheet of FIG. 1; FIG. 3 is a bottom plan view of the abrasive sheet of FIG. 1;

FIG. 4 is a left side view of the abrasive sheet of FIG. 1 (the right side view being a mirror image of the left side view); and,

FIG. 5 is a rear view of the abrasive sheet of FIG. 1. The broken line showing is for environmental purposes only and forms no part of the claimed design. The perforated line extending laterally across the abrasive sheet is illustrative of a perforated line across the abrasive sheet and is part of the claimed design.
